METHOD OF SEALING DRY CELLS

Cyril P. Deibel, Lakewood, Ohio

Application December 13, 1933, Serial No. 702,189

5 Claims. (Cl. 136—175)

This invention relates to a method of forming the seal for dry cells generally and particularly dry cells of the type known as flashlight cells.

One of the main objects of the invention is to provide a method for forming seals for dry cells of the character described which will provide a seal which tightly contacts with the walls of the can and also with the cap covering the carbon electrode.

10 Another object of the invention is to provide a seal for dry cells of the character described which effectively closes the cell and tends to prevent or reduce to a minimum the so-called breathing or gassing of the cell.

15 Another object of the invention is to provide a dry cell of the character described which is provided with a seal which tightly contacts with the zinc can and the brass cap covering the carbon electrode.

20 Further and more limited objects of the invention will appear as the description proceeds and by reference to the accompanying drawing in which Fig. 1 is a view in side elevation of my improved cell with parts broken away to show the seal; Fig. 2 is a top plan view of the cell shown in Fig. 1; Fig. 3 is a view similar to Fig. 1 showing the seal before it has been treated according to my method; and Fig. 4 is a view similar to Fig. 3 showing the plunger or die used for forming or compressing the seal.

25 Heretofore cells of the flashlight type have usually embodied a metal can which contains a mass of mix and a centrally positioned carbon electrode, the mix being insulated from the can by means of a diaphragm of paper or paste or other suitable material. The cell is usually closed by means of a seal which is formed of wax, resin, pitch or other suitable material. The seal is usually poured into the top of the cell while 30 hot and allowed to cool and harden. As the seal cools, it contracts and in so doing tends to pull away from both the zinc can and the metal cap on top of the carbon electrode and this contraction also causes the seal to dish inwardly which has a 35 harmful effect upon the appearance as well as upon the efficiency of the seal. I have provided an improved seal and method of forming the same which will overcome these difficulties.

40 In the accompanying drawing, the reference character 1 designates a zinc can of the type used for flashlight cells and which is enclosed in a paper wrapper or carton 2. The zinc can contains a mass of depolarizing mix which is indicated by the reference character 3 and which is 45 insulated from the zinc can by means of a suit-

able wrapper or liner 4. Arranged in the mass of mix is a centrally disposed carbon electrode 5 the top of which is covered with a brass cap 6. Surrounding the carbon electrode and covering the mass of mix is a lower washer 7 which is 60 formed of cardboard or other suitable material. Also surrounding the carbon electrode is an upper washer 8 which is spaced from the lower washer 7 to provide an expansion chamber. Closing the top of the cell is a layer of sealing 65 material 9 which completely seals the cell and is bonded with the wall of the zinc can and with the brass cap 6. The seal is preferably formed of resin and talc of about equal parts and if a red seal is desired a small amount of iron oxide is 70 added to the mixture. If a blue seal is desired, suitable blue coloring material is added. If desired, black pitch may be used instead of resin.

75 The particular constituents of the mix form no part of this invention and the cell is formed in a manner well known to those skilled in the art.

The seal is poured on top of the upper washer 8 while hot and the can filled up to about the level shown in Fig. 3. In order to provide a more effective bond between the seal and the zinc can 80 as well as with the brass cap I make use of a plunger or die 10 which is shaped as shown most clearly in Fig. 4. After the seal has been poured and has cooled to a suitable temperature, I insert the die 10 into the top of the can to the position 85 shown in Fig. 4.

The die 10 has projections 11 and 12 thereon which form circular depressions 11^a and 12^a in the top of the seal and tend to urge the seal outwardly into firm contact with the zinc can 90 and also inwardly against the brass cap. The temperature and consistency of the seal at this time is such that it retains the shape imparted thereto by the die. In this way I am able to obtain a very effective seal which closely adheres 95 to and bonds with both the zinc can and the cap on the carbon electrode. I am also able to eliminate the difficulties hereinbefore referred to and to prevent the bulging or dishing of the seal which also greatly improves the appearance of 100 the cell.

I may prefer to let the seal cool completely, then reheat the upper portion of the seal, so that it is semi-plastic and then press the die into the seal with the results described above.

105 It will now be clear that I have provided an improved seal for dry cells and a method of forming the same which accomplish the objects of the invention as hereinbefore stated. It is to be understood that various changes may be made 110

in the shape of the die as well as in the constituents of the sealing material without departing from the spirit of the invention as the embodiment of the invention herein disclosed is 5 merely illustrative and is not to be considered in a limiting sense and the invention is limited only in accordance with the scope of the appended claims.

Having thus described my invention, what I 10 claim is:

1. The method of sealing dry cells of the type including a metal can in which is arranged a mass of mix and an electrode having a cap on the upper end thereof, which consists in closing 15 the cell with a mass of soft sealing material disposed in contact with the can and cap and pressing the sealing material while in a plastic condition into firm contact with the metal can and cap.

2. The method of sealing dry cells of the type including a metal can in which is arranged a mass of mix and an electrode having a cap on the upper end thereof, which consists in closing 25 the cell with a mass of soft sealing material disposed in contact with the can and cap and compressing the sealing material while it is in a plastic condition against both the can and cap.

3. The method of sealing dry cells of the type including a zinc can and a carbon electrode hav-

ing a metal cap on the upper end thereof, which consists in pouring hot sealing material into the top of the cell to seal the same and to contact the can and cap, permitting the sealing material to cool to a point where it may be shaped, and compressing the sealing material into firm contact with the zinc can and metal cap.

4. The method of sealing dry cells of the type including a zinc can in which is arranged a mass of mix and an electrode having a metal cap on the upper end thereof, which consists in pouring the seal so that it is in contact with the can and cap, allowing the seal to cool and harden, then reheating the seal to render its upper portion 30 plastic and then compressing the seal outwardly 35 against the zinc can and inwardly against the metal cap.

5. The method of sealing dry cells of the type including a zinc can in which is arranged a mass of mix and an electrode having a metal cap on the upper end thereof, which consists in pouring hot sealing material into the top of the cell in contact with the can and cap, permitting the sealing material to cool and harden, then reheating the upper portion of the seal and 40 compressing the same into firm contact with both the zinc can and the metal cap.
